DESIGN FOR A COMBINATION FOB AND TELESCOPIC PICTURE WALLET

Guenther A. Frank, New York, N. Y.

Application November 29, 1945, Serial No. 124,192

Term of patent 7 years

(Cl. D87—3)

To all whom it may concern:

Be it known that I, Guenther A. Frank, a citizen of the United States, resident of New York, in the county of New York, State of New York, have invented a new, original, and ornamental Design for a Combination Fob and Telescopic Picture Wallet, of which the following is a specification, reference being had to the accompanying drawing, forming part thereof.

In the drawing,

Fig. 1 is a front perspective view of a combination fob and telescopic picture wallet showing my new design in fully closed position.

Figure 2 is a front view thereof in its opened

position showing the picture containing portion in its contracted position.

Figure 3 is a view like Figure 2, showing the picture containing portion in its full extended position, and

Figure 4 is a side view of Figure 3.

The dominant features of the design reside in the portions shown in full lines.

I claim:

The ornamental design for a combination fob and telescopic picture wallet, substantially as shown and described.

GUENTHER A. FRANK.
